United States Patent

Des. 238,359
Patented Jan. 6, 1976

238,359

WRITING INSTRUMENT

Nathan A. Zepell, 1359 Santa Teresita Drive,
Santa Barbara, Calif. 93105

Continuation-in-part of design application Ser. No.
281,920, Aug. 18, 1972, now Patent No. 232,267.
This application Feb. 19, 1974, Ser. No. 443,483

Term of patent 14 years

Int. Cl. D19—06
U.S. Cl. D19—46

FIG. 2.

FIG. 1.

FIG. 3.

FIG. 4.

FIG. 5.

FIG. 1 is a front elevational view of a writing instrument showing my new design, the rear elevational view being substantially identical thereto, except for the clip;

FIG. 2 is a left side elevational view;

FIG. 3 is a right side elevational view;

FIG. 4 is an enlarged scale bottom plan view; and

FIG. 5 is an enlarged scale top plan view.

This application is a continuation-in-part of my co-pending application Ser. No. 281,920, filed Aug. 18, 1972, now Design Pat. No. 232,267.

I claim:

The ornamental design for a writing instrument, as shown and described.
